UNITED STATES PATENT OFFICE.

DALLAS B. CAMPBELL, OF SMITHFIELD, WEST VIRGINIA.

COUPLING-POLE.

No. 838,497.

Specification of Letters Patent.

Patented Dec. 11, 1906.

Application filed January 24, 1906. Serial No. 297,696.

To all whom it may concern:

Be it known that I, DALLAS B. CAMPBELL, a citizen of the United States, residing at Smithfield, in the county of Wetzel, State of 5 West Virginia, have invented certain new and useful Improvements in Coupling-Poles; and I do hereby declare the following to be a full, clear, and exact description of the invention, such as will enable others skilled in the 10 art to which it appertains to make and use the same.

This invention relates to coupling-poles, and more particularly to that class which are used to connect a threshing-machine and a 15 traction-engine when it is desired to back the threshing-machine into a barn or between stacks of hay, thereby permitting use of the engine elsewhere after the threshing-machine has been thus moved.

20 The primary object of the invention is to obviate the movement of the threshing-machine by horse-power, which has been found to be extremely dangerous and inconvenient.

In the accompanying drawings, Figure 1 is 25 an elevation of a portion of a threshing-machine and of an engine, showing the same coupled by means of my coupling-pole. Fig. 2 is a horizontal sectional view on the line 2 2 of Fig. 1. Fig. 3 is a detail view of one of the 30 snap-hook members, and Fig. 4 is a similar view of one of the chain-adjusting devices.

Referring to the drawings, the numeral 5 denotes a threshing-machine, and 6 a traction-engine, and the numerals 7 and 8 denote 35 the front axles of the threshing-machine and traction-engine, respectively. Secured to the front of the bolster of the threshing-machine and the traction-engine are brackets 9, including spaced ears 10, between which are 40 received lips 11 on the ends of a pole 12.

In order that the threshing-machine may be guided during its movement, I provide a suitable steering mechanism, which includes a drum 13, rotatably mounted beneath the 45 threshing-machine 5 and in rear of the bolster of the said machine. The said drum 13 is preferably mounted upon and secured to a shaft 14, which latter is mounted in suitable brackets upon the under side of the said machine and is provided upon one of its ends

with a pinion 15 and is in mesh with a worm-gear 16, carried by the lower end of a rod 17, rotatably mounted in suitable brackets 18 upon the side of the machine, and which is provided at its upper end with a crank-handle 19. 55

Secured upon the axle of the threshing-machine are snap-hook members 19, including each a hook member 20, which has the bill of its hook beveled. Each of the snap-hook members also includes a shank 21, to which is pivoted an arm 22, which has its end beveled to correspond to the bevel of the bill of the hook against which it is adapted to seat. Secured in any suitable manner to the 60 shank 21 is a leaf-spring 23, which has its free end bearing against the arm 22 beyond its pivot-point. 65

Engaged around the drum 13 is a chain 24, which is connected at its ends with eyes 25, 70 formed on one end of threaded stems 26, which is engaged through one of the openings in a turnbuckle 27. Through the other of the openings in said turnbuckle is engaged a threaded stem 28, which is provided at its 75 outer end with an eye 29, arranged for engagement with one of the snap-hook members.

From the foregoing it will be seen that the threshing-machine may be guided during its 80 travel and that the steering-chain may be adjusted when so desired. In case it is desired to make an extremely short turn, in which event the front wheels of the machine would be turned almost at right angles to 85 their normal position, the eye 29 of the stem 28 may be disengaged from the snap-hook members, thereby allowing free movement of the said wheels.

What is claimed is—

1. In a device of the class described the combination with a vehicle and its bolster, of a drum rotatably mounted beneath the vehicle, a chain engaged around the said drum, means carried by the bolster for the detachable connection of the chain therewith, and means for preventing accidental disengagement of the chain therefrom. 95

2. In a device of the class described the combination with a vehicle and its bolster, of 100

a drum rotatably mounted beneath the vehicle, a chain engaged around the said drum, and latch means carried by the bolster for the detachable connection therewith.

5 3. In a device of the class described the combination with a vehicle, of a drum rotatably mounted beneath said vehicle, a chain engaged around said drum and connected at

its ends to the bolster of said vehicle, and means for adjusting the length of said chain. 10

In testimony whereof I affix my signature in presence of two witnesses.

DALLAS B. CAMPBELL.
